UNITED STATES PATENT OFFICE.

MAURICE M. GLASSER, OF CHARLESTON, SOUTH CAROLINA.

CEILING FAN.

Application filed November 8, 1921. Serial No. 513,806.

To all whom it may concern:

Be it known that I, MAURICE M. GLASSER, a citizen of the United States, and a resident of Charleston, in the county of Charleston 5 and State of South Carolina, have invented certain new and useful Improvements in Ceiling Fans, of which the following is a specification.

My invention relates to motor operated 10 fans and particularly, although not necessarily, to ceiling fans, a purpose of my invention being the provision of a ceiling fan which provides simple and efficient means for effecting the bodily oscillation 15 of the fan wheel whereby the air current produced by the fan is continuously diffused over a constantly changing area.

I will describe one form of fan embodying 20 my invention and will then point out the novel features thereof in claims.

In the accompanying drawings:

Figure 1 is a view showing in perspective one form of fan embodying my invention.

Figure 2 is a transverse sectional view 25 looking downwardly.

Figure 3 is a view similar to Figure 2 looking upwardly.

Figure 4 is a fragmentary sectional view 30 of a portion of the gearing comprised in the fan shown in the preceding views.

Similar reference characters refer to similar parts throughout the several views.

Referring specifically to the drawings 35 and particularly to Figure 1, my invention in its present embodiment comprises a pipe or standard A adapted to be suitably fixed at its upper end to the ceiling to provide a support for the entire fan, this standard carrying at its lower end a cup-shaped head 40 H in which is sustained an internal ring gear G, as clearly shown in Figure 3. At a point above the head H, the horizontal portion 15 of a yoke Y is secured, the parallel or vertical portions 16 of the yoke 45 being provided at their free ends with ears 17 that may be secured to or formed integrally with the upper section 18 of a socket member S. The socket member S consists of the upper section 18 and a lower 50 section 19, the latter being also provided with ears 20 which are adapted to aline with the ears 17 and to be secured thereto by fastening members 21 such as screws, bolts or the like. Each section consists of a 55 ring the inner surface of which is concaved

to cooperate with the other ring in providing a socket for the reception of a ball. By virtue of the ears 17 and 20, the two sections are securely held in socket formation and rigidly sustained upon the standard A 60 by means of the yoke Y.

Adapted to work within the socket member S is a ball member B which constitutes the casing of a motor M as shown in dotted lines in Figure 1. The lower end of the 65 motor shaft projects beyond the casing or ball member B and is there provided with the usual fan wheel F. The upper end of the motor shaft which is designated at 22 is operatively connected to a counter-shaft 70 23 through the medium of a reduction train of gearing designated generally at D. The reduction gearing D is housed in a casing K and may be of any suitable form so long as the rotation of the countershaft is 75 sufficiently reduced with respect to the rotational speed of the motor shaft to effect the desired rotation of a pinion P fixed to the upper end of the counter shaft. Because of the distribution of weight, the ball member B normally occupies the position shown in Figure 1 wherein the fan wheel F is inclined with relation to the horizontal and the counter-shaft 23 is inclined with relation to the vertical so that the pinion P 80 at all times meshes with the ring gear G. When the motor operates, the fan wheel F is caused to rotate and upon the driving of the counter-shaft 23 rotation of the pinion P is effected which causes it to traverse 85 the path defined by the ring gear G. Under this movement, the ball member B is caused to rotate about a vertical axis or an axis defined by the standard A, and under such movement the fan wheel F during its rotation by the motor M is also caused to oscillate. By virtue of this movement of the fan wheel a diffusion of the air current produced continuously occurs over a 90 constantly changing area.

It is to be understood that the movement of the ball member B can be varied depending upon the particular form of the gear G. For example, the gear G may be of star formation or elliptical so that with the pinion P constantly meshing therewith a corresponding movement of the ball member B is effected which in turn causes the same movement of the fan wheel F.

An important feature of my invention is 110

the simplicity of construction of the fan, it being manifest that the ball and socket members as well as the pinion and gear can be readily lubricated so as to insure of the 5 smooth and unrestricted operation of the fan. The socket member spans the greatest diameter of the ball member, but being formed of two sections permits removal of the ball member by a detachment of the 10 lower section 19.

It is desirable that the movements of the ball shaped motor casing B relatively to the socket S be restricted to movements which will not result in twisting or straining to the 15 point of rupture the electrical conducting wires leading to the motor casing. When electrical conducting wires, such as indicated at U, are operatively attached to the motor, it is essential that the ball shaped 20 casing B be held against complete rotation in the socket while permitted to oscillate in the manner described. To this end, the socket S has formed in its inner wall an obliquely extending or inclined groove, indicated generally at 24, which groove is 25 formed in the inner walls of both sections of the socket. A projection 25 on the outer wall of the ball shaped motor casing is very loosely received in the groove 24 and 30 co-acts with the latter to prevent the complete rotation of the motor casing relatively to the socket while permitting oscillatory movements of the former about varying axes. The projection 24 may be the head of a set 35 screw fast in the motor casing B as shown.

Although I have herein shown and described only one form of fan embodying my invention, it is to be understood that various 40 changes and modifications may be made herein without departing from the spirit of the invention or the spirit and scope of the appended claims.

What I claim is:

1. A fan comprising a supporting yoke, 45 a socket carried by the yoke, a motor casing of spherical form mounted in the socket, a motor shaft extending from the casing, a fan wheel on the shaft, a counter-shaft operatively connected to the motor shaft, a gear fixed to the yoke, and a pinion on the counter-shaft and constantly meshing with the gear whereby said gear operates to move the motor casing relatively to the socket with a resultant oscillation of the fan wheel.

2. A fan comprising a stationary yoke, 55 a socket fixed to the yoke, a motor casing of spherical form movably mounted in the socket, a motor in the casing, a fan wheel operable by the shaft of said motor, and 60 means operable by the motor for moving the

casing relatively to the socket with the resultant oscillation of the fan wheel.

3. A fan comprising a stationary yoke, a 65 socket fixed to the yoke, a motor casing of spherical form movably mounted in the socket, a motor in the casing, a fan wheel operable by the shaft of said motor, and means operable by the motor for effecting movement of the motor casing to cause a predetermined bodily movement of the fan 70 wheel during its rotation by the motor.

4. A fan comprising a stationary supporting yoke of U-formation, a socket member including a section fixed to the yoke and a 75 socket section removably associated with the yoke, a motor casing of spherical form movably fitted in the socket member and balanced to normally occupy a position wherein in the shaft of the motor is disposed at an angle with relation to the vertical, a fan 80 wheel fixed to the motor shaft, a counter-shaft extending from the motor casing, a reduction gearing operatively connecting the counter-shaft and motor, a pinion fixed to the counter-shaft, and a gear fixed to the 85 yoke and arranged to constantly mesh with said pinion, all for the purpose described.

5. A fan comprising a motor, a fan wheel operable by the motor, a ball and socket mounting for the motor, and means operable 90 by the motor for actuating itself to effect a bodily oscillatory movement of the fan wheel.

6. A fan comprising a motor, a fan wheel operable by the motor, a ball and socket 95 mounting for the motor, said ball and socket mounting being provided with cooperating elements for limiting the movements of the ball member thereof relatively to the socket member thereof, and means for bodily moving the motor within certain limits to effect oscillatory movements of the fan wheel.

7. A fan comprising a supporting yoke, a 100 socket carried by the yoke, said socket being formed with a groove in its inner wall, a motor casing or spherical form mounted in the socket, said casing being provided with a projection loosely received in the said 105 groove for limiting the movements of the casing relatively to the socket, a motor shaft extending from the casing, a fan wheel on the shaft, a counter-shaft operatively connected to the motor shaft, a gear fixed to the yoke, and a pinion on the counter-shaft 110 and constantly meshing with the gear whereby said gear operates to move the motor casing relatively to the socket with a resultant oscillation of the fan wheel.

MAURICE M. GLASSER.
